(57) **CLAIM**

The ornamental design for a beverage container, as shown and described.

DESCRIPTION

This application is related to U.S. Design patent application Ser. No. 29/451,689, entitled “Beverage Container for Retail Sale” by William D. Gamelli and Craig Sawicki, filed on even date herewith, which presents further embodiments of the present invention.

FIG. 1 is a perspective view of a beverage container showing my new design;

FIG. 2 is a top plan view thereof;

FIG. 3 is a side elevational view thereof; and,

FIG. 4 is an exploded view thereof.

In the drawings, the broken lines depict environmental subject matter only and form no part of the claimed design.

1 Claim, 2 Drawing Sheets
